UNITED STATES PATENT OFFICE.

HENRY CLAYTON BIETTE, OF TORONTO, CANADA.

DESIGN FOR A TOY.

SPECIFICATION forming part of Design No. 28,776, dated May 31, 1898.

Application filed February 16, 1898. Serial No. 670,588. Term of patent 3½ years.

To all whom it may concern:

Be it known that I, HENRY CLAYTON BIETTE, merchant, a subject of Victoria, Queen of the United Kingdom of Great Britain and Ireland, and a resident of the city of Toronto, in the Province of Ontario, Canada, have invented and produced a new and original Design for a Toy, of which the following is a specification, reference being had to the accompanying drawings, forming a part thereof.

Figure 1 is a plan view of a toy, showing my new design, Fig. 2 being a sectional view taken on line 2 2 of Fig. 1.

As shown in the drawings, the leading or material features of my design consist of a series of partitions A and chambers B, dis-

posed or arranged as shown in Fig. 1, the said partitions being perpendicular to the plan of the bottom C, as shown in Fig. 2.

The characteristic or leading feature of my design comprises the shape or configuration of the unitary article shown in the accompanying drawings.

Having described my invention, what I claim as new, and desire to secure by Letters Patent, is—

The design for a toy, as herein shown and described.

HENRY CLAYTON BIETTE.
